Des N° 1870

12-1-1863

Instrument to keep the Moon
R. B. Peleg by Leonidas Plumb, Inventor
from 1861 to 1863
Patented Oct 1863

Dec. 1870

George Hills, of Plainville, Conn.
Letters Patent No 1870-Dated Dec 14/1863.

Design for a Clock Dial.

The schedule referred to in these Letters Patent and making part of the same.

To all whom it may concern:

Be it known that I, George Hills, of Plainville, County of Hartford and State of Connecticut, have invented or produced a new and original design for Clock Dial; and I do hereby declare that the following is a full and exact description of the same, referring to the photographic views, in which the same letters indicate like parts.

In the accompanying photographic views is shown a new and original design for a clock dial.

A. is a metallic plate. B. is a circular raised surface configurated with characters which represent the hours and the fractional parts of an hour. C. are inner and outer bevel edges between the raised surface B and the plate A. The whole combined to produce a plain and rich design for a clock dial substantially as described.

What I claim, therefore, and desire to secure by Letters Patent, is the design for a clock dial as hereinabove illustrated and set forth.
